UNITED STATES PATENT OFFICE.

PAUL SCHOOP, OF ZURICH, SWITZERLAND.

SECONDARY BATTERY.

SPECIFICATION forming part of Letters Patent No. 434,093, dated August 12, 1890.

Application filed March 14, 1890. Serial No. 343,829. (No model.)

To all whom it may concern:

Be it known that I, PAUL SCHOOP, a citizen of the Republic of Switzerland, residing at Zurich, in the Republic of Switzerland, have 5 invented a certain new and useful Improvement in Electrodes for Electric Batteries, of which the following is a full, clear, and exact specification.

My invention relates to storage or secondary batteries, and has for its object to construct a cheap, simple, and effective battery.

My invention is illustrated in the accompanying drawings, wherein—

Figure 1 is a plan view of a cell. Fig. 2 is a longitudinal section. Fig. 3 is a detail of one plate, and Fig. 4 of the other. Fig. 5 is a modification of the plate; Fig. 6, a longitudinal section of a cell containing such plates. Figs. 7, 8, 9, and 10 are modifications. 20 Fig. 11 is a plan view of a cell with a different method of connecting. Fig. 12 is a cross-section of the same on the line Y Y; Fig. 13, a portion of a longitudinal section on the line Z Z of Fig. 11 and the line X X of Fig. 12.

25 Like parts are indicated by the same letter in all the figures.

A is the cell-body, of any suitable material. B B are arms from a central stem C and projecting into the side bars D D of ebonite. 30 Each of these arms carries a series of disks E E, which disks, arms and stem, and side bars constitute a plate—for example, a positive plate. The several plates of this character in the cell are connected at the upper 35 ends of their central stems by the connector F. G G are a series of transverse rods connected together at their extremities by the stems H H. The stems H H are connected together on each side by the strips J J, which strips curve 40 toward the front and terminate in a strip K with a conductor L. On the rods or cross-pieces G G are the disks M M, similar to the disks on the rods or arms B B. The use and 45 operation of these parts will readily be understood. The plates consist, substantially as shown, of a series of bars or rods carrying each a series of disks of small dimensions, and the plates are suitably connected in the usual manner. The plates having the lateral 50 connecting-bars H H rest upon strips, and are thus connected, while the plates having the central stems are connected by the strips en-

gaging such central stems at their upper ends in any desirable manner.

The modifications shown in Figs. 5 and 6 55 are as follows: The frame N is provided with the central ring O and the radial bars P P, upon which are placed the similar disks R R. This is the structure for plates which are connected through the middle by means of the 60 rod S, concentric with which rod are series of similar plates, except that intervening between the rod and each of them is a collar of insulating material T. The plates are connected up, alternate plates into one group 65 and the remaining plates into another, one group being connected by the rod S and the other group, for example, by the strips U, of which strips there may be one or more. These plates are kept from contact with each other 70 by the interposed pieces V V.

Figs. 7, 8, and 9 represent modifications of the device, but all retaining substantially the same features as those hereinbefore mentioned—that is to say, all constructed so as 75 to present a thin laterally-extending metallic plate or plates in connection with a supporting stem or portion. Fig. 10 is a detail of a central stem having flanges, as it were. Fig. 11 is a plan view of an element containing such 80 devices as that last illustrated. Fig. 12 is a cross-section of Fig. 11 through the line Y Y, and Fig. 13 is a portion of a longitudinal section on the line Z Z of Fig. 11 and X X of Fig. 12. Like parts are indicated by the same letter in these figures. W is a rod provided with the lateral longitudinal flanges W' W'. W² is a cell. W³ W³ are strips along the bottom of such cell, terminating in the conductor W⁴ at one end. W⁵ W⁵ are strips across the top of 90 the cell, terminating in the conductor W⁶. W⁷ W⁷ are transverse bars, to which one set of rods W W are rigidly secured above, and W⁸ is an insulation in the bottom of the cell, adapted to receive the ends of the rods W W, 95 and thus retain them out of contact with each other. W⁹ is similar insulating material at the top of the cell to keep the upper extremities of the rods W W apart. Each alternate set of rods W W projects through the upper 100 insulation W⁹, and makes contact with the cross-bars W⁷ W⁷, which in turn are in contact with the conductors W⁵ W⁵, leading to the conductor W⁶, while the other set of rods

W¹ W² is rigidly secured to the upper insulation W³ and projects into apertures in the lower insulation W⁴, so as to be brought into contact with the cross conducting-strips W¹⁰ 5 W¹⁰, which lie across the base of the cell and correspond to the upper cross-strip W⁷. These conducting-strips W¹⁰ W¹⁰ are connected with the conductors W³ W³ and thence with the conductor W⁴. Thus each plate virtually consists 10 of a cross-piece, either upper or lower, and a series of rods with flanges, and one set of plates is connected with one conductor above and one with the opposite conductor below. The use and operation of this device, as shown in 15 these figures, are of course apparent without further description, the use and operation being the same as that of other similar devices.

This invention has reference simply to the form of plates, and the disks or flanges or 20 laterally-projecting thin portions or the strips might be of any proper material, and might be continuous with or mechanically or otherwise be applied to the stems, rods, or arms which support them. It is well known that 25 in the large plates, as they are commonly constructed, great difficulty is experienced on account of buckling and on account of the unequal expansion of such plates in the different directions incident to their peculiar shapes 30 and their large masses. The form of device which I have illustrated is calculated to obviate these difficulties by furnishing the active plate or portion of the plate with a strong and firm supporting stem or rod, while the active

plate itself is broken up into a series of small 35 or fragmentary plates not likely to be injured or deformed by the unequal expansion or the contraction thereof.

The flanges W' on the rods shown in Figs. 8, 10, and 12, it will be observed, are simply 40 plates parallel with the length of the rods of which they form part or to which they are secured, and they might be cast upon such rods or otherwise secured to them. The result is the same as that produced, for example, in 45 Fig. 4 or 3, where a series of thin plates parallel to the length of the rods is plunged into the liquid.

Having thus described my invention, what I claim, and desire to secure by Letters Patent, is—

1. As a plate for a storage-battery, a central rod with a series of arms thereon, and a series of thin plates secured on such arms and lying substantially parallel with the axis 55 of the rod.

2. In a storage-battery, the combination of a series of plates connected each alternate one above with one conductor and the other one below with one conductor, each of said 60 plates composed of a series of arms or rods, and a quantity of small plates having active surfaces thereon.

Chicago, Illinois, March 11, 1890.

PAUL SCHOOOP.
